His Attorney

UNITED STATES PATENT OFFICE.

JOHN T. DEMPSTER, OF SCHENECTADY, NEW YORK, ASSIGNOR TO GENERAL ELECTRIC COMPANY, A CORPORATION OF NEW YORK.

ELECTRIC TIMING DEVICE.

1,157,300.

Specification of Letters Patent. Patented Oct. 19, 1915.

Application filed January 3, 1913. Serial No. 740,084.

To all whom it may concern:

Be it known that I, JOHN T. DEMPSTER, a subject of the King of Great Britain, residing at Schenectady, county of Schenectady, State of New York, have invented 5 certain new and useful Improvements in Electric Timing Devices, of which the following is a specification.

My invention relates to electric timing devices, and particularly to devices of that 10 type in which a predetermined act or series of acts of any desired character are set in operation by means of a time actuated mechanism.

15 The objects of my invention are to generally improve the construction of this type of apparatus and particularly to provide, in a device of the character to which this invention relates, an improved and novel construction of time actuated mechanism.

20 A further object of my invention is to provide a novel arrangement of instrumentalities for controlling the time actuated mechanism.

25 The novel features which I believe to be characteristic of my invention will be definitely indicated in the claims appended hereto.

30 The features of construction and the mode of operation will be understood by reference to the following description, taken in connection with the accompanying drawings which show the preferred embodiments of 35 my invention, and in which:

Figure 1 is a perspective view of the novel time actuated mechanism employed in my improved electric timing device, and Fig. 2 is a diagrammatic view in perspective of 40 one of the many applications of my timing device showing the arrangements of the electric circuits.

45 My invention is particularly adapted for use in connection with photograph printing machines, and I have, accordingly, in the accompanying drawings, illustrated such an application of the invention. It will obviously be understood that my electric timing device is in no way limited to this specific application for, as will be readily seen, the 55 timing device is adapted to be used in connection with a great variety of apparatus wherein it is desired to subject the performance of an act or series of acts to the control of a time actuated mechanism or to

control the operation of a member whose movement is to be timed.

Referring to the drawings, there is shown a clock-work mechanism 5 of the ordinary construction mounted upon a supporting base 6. The clock-work mechanism is operatively connected to a driving member 7. This member may be a gear wheel or any suitable driving means for imparting rotation to an actuator 8. The actuator 8 is mounted on a stud shaft 9 secured to one end of a pivoted lever 10. The armature 11 of an electromagnet 12 is secured to the other end of the lever 10.

A pointer like member 13 is operatively secured to the actuator 8, and in the application of my invention illustrated in the drawings the member 13 acts as the movable member of a pair of contacts for controlling an electric circuit, as more fully described hereinafter. A spring 14 is operatively secured to the actuator 8 and member 13 and normally tends to maintain these parts in an initial position, such initial position being determined by a stop 15 with which the upper end of the member 13 engages. An 80 adjustable fixed contact member 16 is mounted in a post 17 secured to the supporting base 6. The member 16 is adapted to be positioned at any desired point on a suitable scale 18 by means of a key shaft 19. 85 The member 16 is also provided with a contact stud 20 which co-operates with a contact pin 21 on the member 13.

In Fig. 2 I have diagrammatically illustrated my invention applied to a photographic printing frame. A slide 22 is adapted to move in the usual manner in the guides 23 of the printing frame. The slide is provided with a lug 24 which engages the armature 25 of an electromagnet 26. The armature 25 thus operates as a catch to hold the slide 22 in an elevated position. It will, of course, be understood that while the slide 22 is in an elevated position the sensitized paper within the printing frame is exposed to a 100 source of light. One terminal of the coil of the electromagnet 26 is connected through lead 27 to the adjustable member 16, while the other terminal of the coil is connected through lead 28 to the movable member 13. 105

The circuit of electromagnet 12 comprises the lead 28 and the lead 29, in which latter is located a circuit closer 30. This circuit

closer is arranged to be operated by the member whose movement is to be timed, which member in the illustration is the slide 22. The circuit closer 30 comprises a fixed 5 contact 31 and a movable contact 32. The movable contact 32 is secured to the end of a pin 33. The pin 33 is in the path of movement of the slide 22, and when the latter is elevated so that the armature or catch 25 10 engages the lug 24 the contacts 31 and 32 will be brought into engagement, thereby completing the electric circuit of the coils of the electromagnet 12.

The operation of my electric timing device will be understood from the foregoing 15 description.

The adjustable member 16 is moved to the desired position on the scale 18 by means of the key shaft 19. The position of the 20 member 16 will determine the length of time that the slide is elevated and the sensitized paper exposed to light. The slide 22 is then raised until the lug 24 is caught by the armature or catch 25. The circuit of the 25 coils of the electromagnet 12 is thereby completed through the closing of contact members 31 and 32. The energizing of electromagnet 12 causes its armature to be attracted, thus rocking the lever 10 and bringing 30 the actuator 8 into operative engagement with the time actuated driving means. The movable contact member 13 then begins to sweep across the scale 18 toward the member 16 at a uniform rate, and after the expiration of the predetermined time as determined 35 by the position of the adjustable member 16, contact 21 engages contact 20, thereby completing the circuit of the electromagnet 26. The armature 25 of the electromagnet is consequently withdrawn from engagement with the lug 24, and the slide 22 drops by gravity and thus closes the printing frame. When the slide 22 drops the engagement of contacts 31 and 32 is 40 broken, thus deenergizing the electromagnet 12. The lever 10 is thereby rocked by gravity, and the actuator 8 disconnected from engagement with the driving member 7. As soon as the engagement of the actuator with 45 the driving member is discontinued, the spring 14 will return the actuator and the movable contact member 13 to their initial positions. This cycle of operation is repeated by again raising the slide 22 so as to 50 close the contacts 31 and 32.

In the drawings I have illustrated the actuator 8 as provided with a rubber tire 34 which is frictionally engaged by the finely toothed periphery of the driving member 7. 60 It will, of course, be understood that any other suitable mechanical arrangement may be employed, as for example, a spur gearing. For convenience in illustration I have shown the slide of the printing frame as the movable member, the same result may obvi-

ously be accomplished in numerous other ways, for example, the printing frame as a whole may be arranged to drop behind an opaque screen. I do not, therefore, desire to be limited to the specific construction 70 shown in the drawings, but aim in the appended claims to cover all modifications which are within the scope of my invention.

As previously noted, my invention is in no manner limited to the specific application 75 illustrated in Fig. 2 of the drawings. I do not desire, therefore, to be restricted in the application of my invention to the particular form of apparatus illustrated and described.

My invention is capable of being employed in any piece of apparatus wherein an electric time actuated mechanism or an electric timing device forms a part of such apparatus, and I accordingly aim in the 85 appended claims to cover my invention broadly without reference to any specific type of apparatus in connection with which it may be employed.

What I claim as new and desire to secure 90 by Letters Patent of the United States, is:—

1. An electric timing device comprising in combination a movable member, an electric circuit including electro-responsive means for retaining said member in a desired position, a time actuated driving means, an actuator adapted to be driven by said time-actuated driving means, circuit-controlling means included in the electric circuit of said electro-responsive means and 100 operatively related to said actuator, means tending to return said actuator to an initial position, electro-responsive means for placing said actuator in operative engagement with said driving means, and circuit-controlling means actuated by the movement of said member to its aforementioned retained position and operatively related to said last mentioned electro-responsive means for making and interrupting the operative engagement between said actuator and said means.

2. An electric time actuated mechanism comprising in combination, a time actuated driving means, an electric circuit including an electromagnet, an armature for said electromagnet, a pivoted lever adapted to be rocked by said armature, an actuator carried by said lever and adapted to engage with said driving means, means tending to 110 return said actuator to an initial position, and means for controlling said electric circuit.

3. An electric timing device comprising in combination, a member whose movement is to be timed, an electric circuit including electro-responsive means for retaining said member in a desired position for a predetermined time, time actuated means for controlling said circuit, a second electric cir- 125 130

cuit including electro-responsive means for controlling said time actuated means, and means cooperating with said member for controlling said second electric circuit.

5. An electric timing device comprising in combination, a member whose movement is to be timed, an electric circuit including electro-responsive means for retaining said member in a desired position for a predetermined time, a fixed contact and a movable contact in said circuit, a time actuated driving means, an actuator adapted to be driven by said driving means and operatively connected to said movable contact, a second 10 electric circuit including electro-responsive means for placing said actuator in operative engagement with said driving means, contacts in said second circuit, and means controlled by said member for operating said 15 last mentioned contacts.

5. An electric timing device comprising in combination, a time actuated driving means, an electric circuit including an electro-magnet, an armature for said electro-magnet, a pivoted lever adapted to be rocked by said armature, an actuator carried by said lever and adapted to engage with said driving means, means tending to return said actuator to an initial position, a fixed contact 20 and a movable contact in said circuit, said movable contact being operated by said

actuator, and a second electric circuit including electro-responsive means for placing said actuator in operative engagement with said driving means and for disconnecting such engagement when said movable contact engages said fixed contact.

6. An electric timing device comprising in combination, a member whose movement is to be timed, an electric circuit including an electromagnet, an armature for said electromagnet adapted to retain said member in a predetermined position, a time actuated driving member, a pivotally mounted actuator adapted to be driven by said driving member, a second electric circuit including an electromagnet adapted to move said actuator into and out of engagement with said driving member, a fixed contact and a movable contact included in said first mentioned electric circuit, said movable contact being driven by said actuator, and contacts for controlling said second mentioned electric circuit and adapted to be closed by said first mentioned member when the latter is 50 in said predetermined position.

In witness whereof, I have hereunto set my hand this 2nd day of January, 1913.

JOHN T. DEMPSTER.
